FOOD PACKAGE

Bennie A. Rafoth and Howard N. Hovland, Appleton, Wis., assignors to Marathon Corporation, Menasha, Wis., a corporation of Wisconsin

Application January 17, 1955, Serial No. 482,144

2 Claims. (Cl. 229—51)

This invention relates to a food package comprising a strippable wrapper or carton and a handle or holder for supporting the food while being consumed after the wrapper or carton is removed therefrom. More specifically, the invention relates to a single service package of frozen comestible, such as ice cream, sherbet, and the like, which is packaged in a carton provided with a handle extending therefrom on which the ice cream and the like is supported after the carton is stripped from the ice cream.

The package is made preferably from a single blank of cardboard and the like which is suitably cut and scored so as to provide a container for receiving and retaining therein the comestible as well as retaining at one portion thereof a suitable handle which extends through the exterior of the carton and into the food contained therein. The carton is also suitably cut and scored so that it may be readily peeled or stripped from the comestible while the food is supported by the handle, thereby leaving the handle supporting the food so that it may be held while being consumed.

Further advantages and details of the invention will be apparent from the following specification and accompanying drawings, wherein

Figure 1 is a plan view of a single paper blank which is suitably cut and scored to provide a carton for the purposes of this invention,

Figure 2 is a transverse sectional view of the carton made from the blank shown in Figure 1,

Figure 3 is a perspective view, partially cut away, showing the completed carton made from the blank shown in Figure 1 and having the bottom flaps in partially closed condition,

Figure 4 is a perspective view of a handle which is adapted to be inserted in the carton shown in Figure 3 for retaining the ice cream and the like thereon when the carton is removed,

Figure 5 is a perspective view of the completed package showing the carton and the handle inserted in final assembled condition,

Figure 6 is a fragmental sectional view taken on lines 6—6 of Figure 5,

Figure 7 is a perspective view showing the first step in stripping the carton from the ice cream packaged therein,

Figure 8 is a perspective view of the package at a later stage of the removal of the carton panels from the ice cream packaged therein,

Figure 9 is still a further stage showing the stripping and tearing of the carton panels from the ice cream block packaged in the carton, and

Figure 10 is a final stage showing the carton completely stripped from the ice cream block while leaving the block of ice cream on the retaining handle with its associated two-panel portions for supporting the ice cream block thereon.

Referring to Figure 1, the carton is made from a single

2

blank which is suitably cut and scored along a series of spaced parallel score lines 1, 2, 3 and 4 to provide a front panel 10, a side panel 11 hinged thereto, a rear panel 12, and a side panel 13. These panels are hinged consecutively along the respective score lines 1, 2 and 3. A plurality of consecutively hinged extension panels 14, 15, 16 and 17 are hingedly connected to panel 13 along score line 4. Panels 14 and 15 are separated by score line 5. Panels 15 and 16 are separated by a partially cut score line 6. Panels 16 and 17 are separated by a partially cut score line 7. Panel 17 is cut out at its free edge to provide a plurality of tooth-like portions indicated by numeral 17a. Panels 16 and 17 are adapted to be folded over on cut score line 6 and are then glued on their inner surface to the overlapped portions of panels 14 and 15, as shown in Figure 2, whereby panels 15 and 16 will provide a grasping portion for opening the carton. Panel portions 16 and 17 are adapted to be folded over the free edge portion of the front panel 10 and adhered thereto by means of adhesive which is applied only to the areas delineated by the tooth-like portions 17a of panel 17 so as to form a tubular carton as shown in Figure 2.

Front panel 10 is provided with an upper closure flap 18 and a lower closure flap 19, hinged respectively along score line 27 and perforation 26. Flap 18 is provided with a slit 18a for receiving a locking tongue. Lower flap 19 is provided with a cut-out portion 19a for a purpose which will be explained later. Side wall 11 is provided with an upper closure flap 20 and a lower closure flap 21. Closure flap 18 is separated from the flap 20 along cut line 36. Lower closure flap 21 is separated from flap 19 along cut score line 37. Flap 21 is provided at its medial portion with a slit 45 extending parallel to the perforated or cut score line 28 along which flap 21 is hinged to the side wall 11. It is essential to have score line 28 cut or perforated so that it is readily detachable from side panel 11. Transverse cut lines 47 are provided at each end of the slit 45 and spaced score lines 46 are positioned so as to connect with the ends of the slits 47 so as to provide small hinged panels 21a in the flap 21 for purpose which will be described later. The upper closure flap 20 is hinged to side wall 11 along perforated or cut score line 29 which terminates a short distance from the score line 1 along an unperforated length of the score line indicated by numeral 29a for a purpose to be described later. Rear wall 12 is provided with a closure flap 22 hinged thereto along score line 31. The flap 22 is provided with a tongue portion 22a which is adapted to be received in the slit 18a of panel 18. A lower closure flap 23 is hinged to the rear panel 12 along a cut or perforated score line 30 so that flap 23 may be readily separated from wall 12 for a purpose to be explained. A slit 40 is provided in the medial portion of the closure flap 23 which is intersected by two spaced cut lines 42 at the ends thereof. The ends of the cut lines 42 are connected by perforated score lines 41 in order to provide two small flap portions 23a adjacent the slit 40 for a purpose which will be described later. The flap 23 is separated from the flap 21 along the slit line 35. The flap 22 is separated from the flap 20 along the slit line 34. The side wall 13 is provided with an upper closure flap 24 hinged thereto along score line 33 and a lower closure flap 25 hinged thereto along score line 32, which may be perforated if desired.

In forming a carton from the blank, as described, adhesive is applied to the upper surface of panels 16 and 17 and they are folded over and adhered to panels 15 and 14. The blank is then folded over along score line 2 in the manner shown in Figure 2 and then adhesive is applied to the exposed surface of panel 17 which is

superimposed on the front wall 10 by folding the combined panels 14, 15, 16 and 17 on their hinge line 4 in a manner shown in Figure 2, whereupon the blank will be formed into a tubular container as shown in Figure 3.

The package is formed by setting up the walls 10, 11, 12 and 13 thereof into right angular relation, as shown in Figure 3, and then the top is closed by first folding flap 20 inwardly of the carton, then folding flap 24 thereover, then folding flaps 18 and 22 over the previously folded flaps so as to permit the tongue 22a to enter the slot 18a provided in flap 18 into locking engagement. Ice cream or other suitable comestible is then poured through the open lower end of the carton and when the carton is filled, the lower closure flaps are suitably closed by folding over the panel 21, then folding thereover the panel 25, then folding in the panel 19 and finally folding panel 23 thereover. A handle 50 is then inserted through the slit 40 in panel 23 and then through the slit 45 in panel 21 and into the relatively soft contained comestible, in the manner shown in Figure 5. The cut-out portion 19a permits passage of the handle 50 through the slits 40 and 45. Instead of a cut-out portion 19a, a slit may be provided in flap 19 to permit handle 50 to pass therethrough. As the handle 50 is inserted through the slits in panels 21 and 23, the small hinged panel portions 21a provided in panel 21 and small hinged panel portions 23a in flap 23 will be folded inwardly of the carton as shown in Figure 6. These panels 21a and 23a will tend to spring back to their original position and thereby will engage the surface of the handle 50 and thus frictionally retain same in tight engagement.

The finished package will have the appearance shown in Figure 5. The ice cream and the like packaged as described is now suitably frozen and can be stored and shipped as may be desired.

When it is desired to consume the ice cream or other comestible packaged within the carton, it is merely necessary to grasp the tear flap 15 so as to tear the tongue portions 17a from adhesion to the front panel 10 in the manner shown in Figure 7. The fibers of the panel 17 will split apart leaving part of the fiber 17a adhering to the front panel 10 as shown in Figure 7. Upon pulling the tear flap 16 to the left as shown in Figure 7, the side wall 13 and the hinged upper and lower flaps 24 and 25 will be disengaged from the remaining portions of the carton as shown in Figure 7. Upon further pulling, the carton panels will assume the position shown in Figure 8, the panel 12 being separated at its lower portion along the perforated score line 30, leaving the flap portion 23 in engagement with the handle 50. At the same time, the upper closure panel 22 will be disengaged from the slit 18a provided in flap 18. Upon further pulling of the carton panels in the manner shown in Figure 9, the side panel 11 will be separated from its upper flap 20 and its lower flap 21 by virtue of the perforated score line 29 provided at the upper closure flap 20 and along the perforated score line 28 provided at the lower closure flap 21. It will be noted that the lower flap portion 21 will be completely severed from the panel 11 and will be retained on the stick 50 as shown in Figure 9, whereas the upper flap portion 20 will not be completely disengaged from the panel portion 11, but will remain attached thereto along the scored hinge line 29a which is not perforated. Upon further pulling and extending the panel portions in the manner shown in Figure 10, the entire carton will be removed from the block of ice cream A except that the two flap portions 21 and 23 will remain in engagement with the handle 50 and form a bottom support for the block of ice cream A. It will thus be noted that all the panel portions including all the flap portions are easily stripped or peeled from the ice cream block A and there will remain left on the block of ice cream A only the two lower flaps 21 and 23 through

which the handle 50 extends through the slits provided therein.

The present construction provides a very convenient manner of distributing single service portions of ice cream or the like in a carton which can be readily packaged and provided with a handle for supporting and holding the ice cream while it is being consumed. The panel portions of the carton can be readily stripped from the block of ice cream and the like without soiling the fingers and without requiring any manipulative actions whatsoever except merely a single pull of the hand outwardly of the block of ice cream in one direction therefrom. As soon as the panels of the carton are stripped from the ice cream block as described, the ice cream is readily available for consumption while supported on a convenient handle and two flap portions of the carton.

The present invention thus provides a very convenient mode of packaging ice cream, frozen sherbets, ices and the like which can be conveniently packaged with a handle and readily consumed without requiring the use of dishes, spoons and the like. The present package can be sold in small units sufficient for consumption at one time. The carton may of course be printed with suitable indicia, trade-marks and the like to indicate the origin of the goods. It will be apparent that the package comprises essentially a tubular container constituted of rectangular panels which are provided with end flaps to form a top and bottom closure. A suitable tear-flap connected to one of the side panels permits removal of all the side panels from the block of ice cream packaged therein. At the same time the closure flaps are also stripped or removed together with the side panels, except that two closure flaps are left behind in supporting relation on the handle upon which the ice cream rests while it is being consumed.

It is to be understood that the specific description previously given is intended to be merely illustrative of the principles of the invention herein involved and it is to be understood that changes and modifications may be made in the specific construction which are intended to be included within the scope of the appended claims.

We claim:

1. A carton for packaging a block of a comestible therein and for receiving a handle, the carton being formed from a single blank suitably cut and scored to provide a front wall, a first side wall, a rear wall and a second side wall, said walls being hingedly connected by score lines, a glue panel hingedly connected to said second side wall, said glue panel being adapted to be folded over and adhered to the said front wall, each of said front, rear and side walls being provided with closure flaps at their upper and lower portions, the upper closure flap of the said front wall being provided with a slit portion for engagingly receiving a tongue portion therein, the upper closure flap of the rear wall being provided with a tongue portion for engagement in the slit portion of said closure flap of the front wall, the upper closure flap of said first side wall being hingedly connected to said wall along a perforated score line extending substantially the entire length of said side wall but stopping short of the hinge line connecting said side wall to said front wall, the lower closure flap of said first side wall being provided with a handle-receiving internal slit extending parallel to the hinge line of said closure flap, the lower closure flap of said rear wall being provided with an internal slit for receiving a handle therethrough and extending along a line perpendicular to the hinge line connecting said rear wall and said lower flap, said lower closure flap of said first side wall and said lower closure flap of said rear wall being hingedly connected to said walls along perforated hinge lines, whereby upon pulling the said glue panel and releasing same from the said front wall the walls, upper closure flaps and front and second side wall bottom closure flaps are strippable from the block of the comestible which may be retained in

said carton while leaving the said two lower flaps having said slits disconnected from said first side wall and rear wall in frictional engagement with the handle inserted therethrough and in supporting relation to such block of comestible.

2. A carton for packaging comestibles and the like formed from a single blank suitably cut and scored to provide a front panel, an upper closure flap hingedly connected to said front panel, said upper closure flap being provided with a slit for receiving a locking tongue 10 therein, a closure flap hingedly connected along a score line to the opposed end of said front panel, a side wall hingedly connected to said front wall along a scored hinge line, an upper closure flap hingedly connected to said side wall along a perforated score line extending 15 substantially the entire length of said side wall but stopping short of said scored hinge line, whereby said upper closure flap may be disconnected from said side wall except for a short portion adjacent the said scored hinge line, a lower closure flap hingedly connected to said side wall along a perforated score line along which said lower flap is adapted to be severed from said side wall, an internal slit provided in the medial portion of the said lower flap, slit and score lines provided adjacent said slit for forming hinged panel portions adapted to be folded inwardly of said lower flap upon inserting a handle therethrough, a rear wall hingedly connected to said side wall along a score line, an upper closure flap hingedly connected to said rear wall, said upper closure flap being provided with a tongue portion adapted to be received 20 in the slit provided in the upper closure flap of said front wall, a lower closure flap hingedly connected to said rear wall along a perforated score line whereby said lower

closure flap is adapted to be separated from said rear wall, said last-mentioned lower flap being provided with an internal slit for receiving a handle therethrough, said slit being positioned in perpendicular relation to the slit in said side wall lower closure flap, slits and score lines provided adjacent said slit in said rear wall lower closure flap to provide hinged panel portions adjacent said slit whereby said panel portions may be folded inwardly of the blank upon inserting a handle therethrough, a second side wall hingedly connected to said rear wall along a score line therebetween, closure flaps hingedly connected to the upper and lower portions of said second side wall, a glue panel hingedly connected to said second side wall, said panel being folded back upon itself and adhered at the overlapped contacting portions thereof to provide a grasping panel, said grasping panel being adapted to be folded over and the portion thereof adjacent its hinge connection to the second side wall adhered to said front wall and adapted to be grasped and releasably separated from said front wall.
